UNITED STATES PATENT OFFICE.

KEMP S. GRAHAM, OF PHILADELPHIA, PENNSYLVANIA, ASSIGNOR TO THE ORINOKA MILLS, OF PHILADELPHIA, PENNSYLVANIA, A CORPORATION OF NEW YORK.

JACQUARD-CARD-PUNCHING MACHINE.

Application filed March 15, 1923. Serial No. 625,373.

To all whom it may concern:

Be it known that I, KEMP S. GRAHAM, a citizen of the United States, residing in Philadelphia, Pennsylvania, have invented 5 a Jacquard - Card - Punching Machine, of which the following is a specification.

My invention relates to machines for stamping jacquard cards, and more particularly to that type of machine known as the 10 piano card stamping machine.

The main object of the invention is to provide a machine of this type by means of which cards may be punched in practicable manner for the so-called "straight-through" 15 tie up of the loom, which operation with the present form of machine is practically impossible.

A further object of the invention is to provide means whereby machines of this 20 type may be employed for duplicating.

The invention further contemplates the provision of novel mechanism which in conjunction with a master card prevents the stamping of holes in any other but the 25 proper points upon the card.

In the attached drawings:

Figure 1, is a side elevation of the essential portions of a machine made in accordance with my invention;

Fig. 2, is a front elevation of the machine;

Fig. 3, is a fragmentary plan view illustrating the principal details;

Fig. 4, is a side elevation of that portion of the mechanism illustrated in Fig. 3;

Fig. 5, is a section on the line 5—5, Fig. 4;

Fig. 6, is a section on the line 6—6, Fig. 3, and

Fig. 7, is a section on the line 7—7, Fig. 3.

With reference to the drawings, the machine is of the same general construction as the machines of this type now in general use, comprising a frame 1 having at the top a table 2, upon which travels a carriage 3 provided at its forward end with means for clamping one end of a card. Near the forward end of the table 2 is mounted upon vertical slides 4 a punching-head 5, which head contains the punches by means of which the cards are perforated, this head

50 being provided with the usual set of keys 6 by means of which the desired punches, designated in the drawings by the reference numeral 7, are thrown into operation. The slides 4 with the head 5 are reciprocated

vertically by means of treadles 8 and 9, depression of which respectively elevates and depresses the head. The slides 4, 4, are provided with a cross head 10, in which is pivotally secured intermediate its ends a lever arm 11. The forward end of this arm 11 is fulcrumed at the top of a vertical arm 12 pivotally secured at 13 to a cross beam 14 of the frame 1, the arrangement being such that elevation or depression of the rear end of the arm 11 effects a vertical reciprocation of the cross head 10 and of the guides 4 to which the cross head is secured. The rear end of the arm 11 is connected through rods 15 and 16 and a rock arm 17 secured to the under side of the table 2 to the treadle 8, the treadle 9 also being connected to the rear end of the lever 11 through a connecting rod 18. As previously stated, by means of the foregoing apparatus depression successively of the levers 8 and 9 effects a vertical reciprocation of the punching-head 5. The usual means also is provided for intermittently advancing the carriage 3 on the table 2, this movement synchronizing with the movement of the punching-head 5. Movement of the carriage 3 is provided for in the usual manner by operatively connecting the treadle 8 with an escapement mechanism, so that at each downward movement of this treadle 8, the carriage under influence in the present instance of an attached weight 19 is permitted to advance a predetermined distance towards the rear of the machine and away from the punching-head 5.

The escapement, which comprises a rack 20 at one side of the carriage and a pair of vertically movable spaced blades 21 and 22 is actuated from the treadle 8 through a rock lever 23 mounted on the table 2 at one side of the carriage and to which the blades 21 and 22 are operatively connected, and a rod 24 which connects the forward end of the lever 23 to the treadle 8. The blades 21 and 22 are carried by a block 25 having a lateral extension 26 which projects into a horizontal slot 27 in the rear end piece 28 of the lever 23, the arrangement being such that oscillation of the rock lever 23 will effect a vertical reciprocation of the block 25 which is guided in its vertical movement by two upright pins fastened to the table 2. A transverse arm 29 secured to the block 25

bridges the path of the carriage 3 and has on the outer end a vertical guide pin 30 slidable in a guide 31 secured to the table 2.

In so far as described, the mechanism is 5 identical in substance with a well known standard machine of the type involved, and the operation of the mechanism will be understood by those acquainted with the art.

The transverse arm 29, as illustrated in 10 Fig. 7, comprises in that portion overlying the path of the carriage 3, horizontal and parallel branches 32 and 33, and vertically slidable in these branches are a series of pins 34 which correspond in number to the 15 punches 7 of the punching-head and which occupy similar relative positions, the pins 34 being in alignment with the path of the carriage 3 and with the respective corresponding punches 7.

Secured to the top of the carriage 3 is a 20 platform or table 35 adapted for reception of a master card, designated in the drawings by the reference numeral 36, means being provided such as a peg 37 for retaining the card in place upon the platform. The platform 35 is perforated over its entire 25 length, the perforations being in transverse rows the distance between which corresponds exactly to the distance to which the carriage is permitted to move by the previously described escapement. Each row of these apertures contains perforations corresponding in number to the number of 30 punches 7 and of the pins 34, and the individual perforations in each row are correspondingly spaced. Each of the pins 34 is provided with a spring 38 which tends to move the pin downwardly to the point where its lower end rests upon the surface of the 35 card 36 or, where the card is perforated, to a detruded position, illustrated in Fig. 7, which is governed by stop pins 39 extending laterally through the pins 34 and constituting also an abutment for the lower ends of 40 the springs 38. Each of the pins 34 is pivotally secured to one arm of a bell crank lever 40, which levers are loosely mounted upon a shaft 41 extending transversely of the table 2 and mounted in the tops of a pair 45 of uprights 42, 42, secured to the table. The other arms of these bell crank levers 41 are secured by means of reach rods 43 to a series of blocks 44 slidably mounted in horizontal recesses in the side of the punching-head 5, as best shown in Figs. 5 and 6. As 50 clearly illustrated, one of the blocks 44 underlies each of the keys 6, and the inner ends of the recesses in which the blocks move overlie respectively the punches 7 when the latter are in the normal depressed position.

Each of the blocks 44 is provided at its inner end with a vertically slidable pin or plunger 45 which occupies a vertical passage in the inner end of the block, the pins 55 being retained within the passages by a

collar 46 which normally rests upon an internal shoulder 47 in the blocks. The pins 45 when the blocks 44 are in the positions illustrated in Fig. 6 directly overlie and are in alignment with the punches 7 so that 60 elevation of the punch in the head will effect a corresponding elevation of the pin 45. The keys 6 are normally held in an extruded position by a spring 50, and in this position the inner ends of the keys lie outwardly of the inner end of the blocks 44 and of the pins 45 whereby the said pins 45 are free to move upwardly. When, however, the keys 6 are pressed inward, the inner ends thereof are brought directly over 65 the tops of the apertures in the blocks 44 occupied by the pins 45 whereby elevation of the pins is prevented. Retraction of the blocks 44, in a manner hereinafter described, whereby the inner ends of the blocks are made to clear the tops of the 70 punches 7 permits elevation of the punches regardless of the position of the keys 6.

In the position of the block 25 illustrated 75 in Fig. 7, it will be noted that the pins 34 rest upon the unperforated portions of the master card 36, while those pins which overlie perforated portions pass through the card and through the platform 35. As a 80 result of the detruded positions assumed by these latter keys, which are designated in the drawings by the reference numeral 52, those of the bell crank levers 40 which connect with these pins 52 are so moved, under the action of the springs 38, as to advance 85 the rods 43 and to move the blocks 44 inwardly in the head 5 to the position illustrated in Fig. 6. With the blocks 44 in this 90 position and with the key 6 in its inner position, the punch 7 is prevented from moving upward. Those of the pins 34, however, which rest upon the top of the card 36 retain the bell crank levers 40 to which they are 95 attached in such position that the blocks 44 are held in their retracted, outer positions 100 in which the inner ends of the blocks lie clear of the tops of the punches 7 whereby the punches are permitted to move upwardly in the head regardless of whether the key 6 is in or out.

It will also be noted that at each upward movement of the block 25, those of the pins 34 which have passed through apertures in the card 36 and the platform 35 are first elevated out of these apertures to the position of those of the pins 34 which rest upon the top of the card 36, and an additional final upward movement of the block 25 effects an elevation of the entire set of pins 34 above the top surface of the card, thereby breaking contact between the pins and the card 36 during the advance movements 110 of the carriage 3.

The operation of the machine is as follows: A blank card, designated in Fig. 4 115

by the reference numeral 53, is passed under the punching-head 5 and its inner end secured by means of the usual clamp 54 to the forward end of the carriage 3. An operating lever 54^a is provided on the carriage for manipulating this clamp 54. The operator with a color chart before him then manipulates his keys 6 in accordance with the chart. Previous to the starting of the machine, however, the master card 36 has been placed upon the platform 35 of the carriage, this master card being so perforated as to permit the punching of the card 53 only in accordance with the particular tie-up of the machine with which the card 53 is to be used. This control is effected through the pins 34 and the blocks 44 to which they are connected, since only when the pins 34 are permitted to pass through the card 36 is it possible for the corresponding punch 7 in the punching-head to perforate the card 53. The operator accordingly need not keep in mind the tie-up and need manipulate the keys 6 only in accordance with the color arrangement of the color chart, the keys being manipulated as a unit. The operator operates the treadles 8 and 9 in the usual manner to depress and elevate the punch-head, each depression of the lever 8 resulting in an elevation of the head and the depression of the forward end of the lever 23 with a resultant actuation of the escapement to permit a rearward movement under the action of the weight 19 of the carriage 3. Each actuation of the escapement to release the carriage 3 also results, as previously described, in an elevation of the pins 34 clear of the card 36 whereby the pins 34 do not interfere with the following movement of the carriage.

When it is desired to move the carriage forward to the starting position, a third treadle 55 is provided which is connected by means of a rod 56 with the forward end of the lever 23 whereby depression of the treadle 55 elevates the lower blade 22 of the escapement clear of the top of the rack and thereby permits advancement of the rack by means, in the present instance, of a flexible element 57 such as a rope which is attached to the carriage and which is carried forward to a position available to the operator.

It will be noticed that the rod 56 passes through an aperture in the forward end of the lever 23 and is provided with a nut at its upper end which, when the rod is depressed with the lever, carries the lever 23 downwardly, the arrangement, however, leaving the lever 23 free to move downward under operation of the treadle 8 without affecting the treadle 55, which is normally retained in an elevated position by a spring 58.

The great advantages of this invention will be recognized by those familiar with the art, since it enables the cutting of cards for certain types of tie-up which heretofore could not be cut in practicable manner upon this type of machine. The device thus greatly increases the scope of this type of machine as well as materially facilitating the cutting of all cards. The device further permits duplication by the simple expedient of placing the card which is to be duplicated up on the platform 35, and after pressing all of the keys 6 manipulating the treadles 8 and 9 until the card is completed.

I claim—

1. The combination with a supporting body having a recess, of a punch slidable in said recess, and a pair of elements independently movable into said recess in back of the punch and adapted in predetermined relative positions to fix the punch in the body.

2. The combination with a supporting body having a recess, of a punch slidable in said recess, an element movable into the recess in back of the punch, a pin slidably mounted in said element and adapted to occupy a position in alignment with the punch when the element enters the recess and to be engaged by the inner end of the punch, and a second element independently movable into the recess in back of said pin and adapted when in the recess to constitute an abutment for the pin preventing movement in the body both of the pin and the punch.

3. The combination with a supporting body having a recess, of a punch slidable in said recess, an element movable into the recess in back of the punch, a pin slidably mounted in said element and adapted to occupy a position in alignment with the punch when the element enters the recess and to be engaged by the inner end of the punch, a second element independently movable into the recess in back of said pin and adapted when in the recess to constitute an abutment for the pin preventing movement in the body both of the pin and the punch, means adapting one of said elements for manual operation, and mechanism for automatically operating the other element.

4. The combination with a supporting body, of a punch slidable in the body, an element adjustable into the path of the punch and adapted for movement with the punch, and a second element adjustable into the path of the first element and adapted when so adjusted to prevent movement of said first element and of the punch in the body.

5. The combination with a supporting body, of a punch slidable in the body, an element adjustable into the path of the punch and capable of movement in the supporting

body with the punch, mechanism for automatically actuating the element in accordance with a variable master control means, a second element movable into the path of the 5 first and constituting when in said path a stop preventing movement in the head of the said first element and of the punch, means normally retaining the second element clear of the path of the first, and means providing for manually moving the second element into said path.

6. The combination with a supporting body, of a punch slideable in the body, an element adapted for actuation by the punch, 15 means for adjusting said element into the path of the punch and for withdrawing the element, and a second adjustable element adapted to constitute a stop of the first preventing actuation by the punch and movement 20 of the punch in the body.

7. The combination with a supporting body, of a punch movably supported in the body, an element adapted for actuation by the punch, means for making and breaking 25 the operating connection between the punch and said element, and an adjustable stop for said element, adapted when operative to prevent actuation of the element and movement of the punch in the body.

30 8. The combination with a supporting body, of a plurality of punches movably supported in the body, a corresponding number of independent elements adapted for actuation by the respective punches, automatic 35 means for selectively making and breaking the operating connections between the punches and the respective corresponding elements, a stop for each of said elements, and means whereby the stops may be manually 40 adjusted to operative and inoperative positions, said stops when operative preventing actuation of the elements and movement of the associated punches in the body.

45 9. The combination with a supporting body, of a plurality of punches movably supported in the body, an element for each of said punches adapted for actuation by the punch with which it is associated, means including a movable member operatively 50 connected with each of said elements for making and breaking the operating connection between the punches and their respective elements, a variable master member controlling the positions of said movable members, 55 and a manually operated stop for each of said elements adapted when operative to prevent movement of the associated punches in the body.

60 10. The combination with a supporting body, of a member movable in the body, and a stop for preventing movement of the member in the body comprising a pair of independently adjustable elements each dependent for effectiveness upon the other.

65 11. In a punching machine, the combina-

tion with a punch-head, of a plurality of punches projecting from and adapted under pressure to retreat into the head, of means for selectively preventing such inward movement comprising for each punch two independently movable stop elements, one manually adjustable, and mechanism including a variable master control for adjusting the other element.

70 12. In a punching machine, the combination with a punch-head, of a plurality of punches projecting from and adapted under pressure to retreat into the head, of means for selectively preventing such inward movement comprising for each punch two independently movable stop elements, each incapable without the other of effective operation, manual means for adjusting one of said stop elements, a member operatively connected with the other stop element and adapted to determine by its position the adjustment of the stop element to which it is connected, and means including a master element for controlling the position of said members.

75 13. In a punching machine, the combination with a punch-head, of a plurality of punches projecting from and adapted under pressure to retreat into the head, of means for selectively preventing such inward movement comprising for each punch two independently movable stop elements, each incapable without the other of effective operation, manual means for adjusting one of said stop elements, a member operatively 90 connected with the other stop element and adapted to determine by its position the adjustment of the stop element to which it is connected, a support for a perforated master element, and resilient means tending to hold said members against the face of the master element and when registering with the perforations to force said members to an advanced position.

95 14. In a punching machine, the combination with a plurality of punches, of means for supporting an article in position to be operated upon by the punches, mechanism for advancing the article between punching operations, and mechanism determining the operativeness of the punches comprising a pair of stop elements associated with each punch, means movable with the article for supporting a master element, means providing for manual adjustment of one stop element of each pair, and mechanism controlled by the master element and operatively connected with the others of the stop elements.

100 15. In a punching machine, the combination with a plurality of punches, of articles supporting means, and mechanism for effecting a relative reciprocation between the punches and the support, mechanism for advancing the article between punching operations, and mechanism for determining the 105 110 115 120 125 130

operativeness of the respective punches during each reciprocation comprising means movable with the article for supporting a master element, a plurality of elements operatively connected respectively with the punches, means tending to retain the elements in contact with the master element, and means operatively associated with the said reciprocating mechanism for elevating the elements clear of the master element during the advance movements of the latter with the article.

KEMP S. GRAHAM.
